(57) **CLAIM**

The ornamental design for a rotary cutting tool, as shown and described.

DESCRIPTION

FIG. 1 is a front view of a rotary cutting tool in accordance with Embodiment 1 of the present design;

FIG. 2 is a back view thereof;

FIG. 3 is a right view thereof;

FIG. 4 is a left view thereof;

FIG. 5 is a top view thereof;

FIG. 6 is a bottom view thereof;

FIG. 7 is a perspective view thereof;

FIG. 8 is a partial enlarged view of portion 8 of FIG. 1;

FIG. 9 is a partial enlarged view of portion 9 of FIG. 2;

FIG. 10 is an enlarged left view thereof;

FIG. 11 is a partial enlarged view of portion 11 of FIG. 5;

FIG. 12 is a partial enlarged view of portion 12 of FIG. 6;

FIG. 13 is a partial enlarged view of portion 13 of FIG. 7;

FIG. 14 is a cross sectional view taken along line 14-14 of FIG. 1;

FIG. 15 is a front view of a rotary cutting tool in accordance with Embodiment 2 of the present design;

FIG. 16 is a back view thereof;

FIG. 17 is a right view thereof;

FIG. 18 is a left view thereof;

FIG. 19 is a top view thereof;

FIG. 20 is a bottom view thereof;

FIG. 21 is a perspective view thereof;

FIG. 22 is a partial enlarged view of portion 22 of FIG. 15;

FIG. 23 is a partial enlarged view of portion 23 of FIG. 16;

FIG. 24 is an enlarged left view thereof;

FIG. 25 is a partial enlarged view of portion 25 of FIG. 19;

FIG. 26 is a partial enlarged view of portion 26 of FIG. 20;

FIG. 27 is a partial enlarged view of portion 27 of FIG. 21;

FIG. 28 is a cross sectional view taken along line 28-28 of FIG. 15;

FIG. 29 is a front view of a rotary cutting tool in accordance with Embodiment 3 of the present design;

FIG. 30 is a back view thereof;

(Continued)

FIG. 31 is a right view thereof;
 FIG. 32 is a left view thereof;
 FIG. 33 is a top view thereof;
 FIG. 34 is a bottom view thereof;
 FIG. 35 is a perspective view thereof;
 FIG. 36 is a partial enlarged view of portion 36 of FIG. 29;
 FIG. 37 is a partial enlarged view of portion 37 of FIG. 30;
 FIG. 38 is an enlarged left view thereof;
 FIG. 39 is a partial enlarged view of portion 39 of FIG. 33;
 FIG. 40 is a partial enlarged view of portion 40 of FIG. 34;
 FIG. 41 is a partial enlarged view of portion 41 of FIG. 35;
 and,
 FIG. 42 is a cross sectional view taken along line 42-42 of FIG. 29.
 The broken lines shown in the drawings represent portions of the rotary cutting tool that form no part of the claimed design.
